No. 12,720

Jan. 31, 1882

UNITED STATES PATENT OFFICE.

OLIVER B. KEELEY, OF SPRING CITY, PENNSYLVANIA.

DESIGN FOR A HEATING-STOVE.

SPECIFICATION forming part of Design No. 12,720, dated January 31, 1882.

Application filed December 19, 1881. Term of patent 7 years.

To all whom it may concern:

Be it known that I, OLIVER B. KEELEY, a citizen of the United States, and a resident of Spring City, Chester county, Pennsylvania, have invented a Design for a Heating-Stove, of which the following is a specification.

My design for a heating-stove is fully shown in the accompanying drawing.

The design comprises the urn A, magazine-section B, illuminating-section D, fire pot section E, ash-pit section F, base G, and flue-casing H.

The urn comprises the body, rim, and arms, and has a flaring base, all as too fully shown to need detailed description.

The section B is divided by columns *a* into segments, each of which has a central panel, *b*, the columns and panels being ornamented with line-engraving, as shown.

The sections D and E have the usual doors with mica-covered openings, and the section F has the dampered openings and side panels, *d*.

The base G comprises the skirting *e* and feet *f*, engraved as shown; and the flue-casing H ²⁵ has three sections, *g*, *g'*, and *g''*, with ornamentation in relief.

Some of the features of the ornamentation of the stove are shown and claimed in a separate application filed by me simultaneously ³⁰ herewith. Hence I do not claim in the present application the features of the design independently considered; but

I claim—

The design for a heating-stove, said design ³⁵ comprising the urn A, sections B, D, E, and F, base G, and flue-casing H, all ornamented, as shown and described.

In testimony whereof I have signed my name to this specification in the presence of two sub- ⁴⁰ scribing witnesses.

OLIVER B. KEELEY.
